ATTORNEY

UNITED STATES PATENT OFFICE.

OLIVER MITCHELL, OF BROOKLINE, MASSACHUSETTS.

FOUNTAIN PEN.

Application filed January 14, 1922. Serial No. 529,204.

To all whom it may concern:

Be it known that I, OLIVER MITCHELL, a citizen of the United States, residing at Brookline, in the county of Norfolk and 5 State of Massachusetts, have invented certain new and useful Improvements in Fountain Pens, of which the following is a specification.

In the drawings:

10 Figure 1 is a longitudinal sectional elevation of a fountain pen embodying my invention;

Figure 2 is a cross-section on line 2—2 of Figure 1;

15 Figure 3 is a cross-section on line 3—3 of Figure 1;

Figure 4 is a perspective view of the disk G;

20 Figure 5 is a longitudinal view partly in section of the upper or rear part of the device of Figure 1, the interior mechanism being as at the upper or rearward stroke of the rod e.

As shown in the drawings, A is a fountain 25 carrying at one end an ink feed bar B, supporting in proper position a pen C and at the other end a gland D having a central perforation d. Within the fountain is contained a chamber E closed at the rear end 30 and fitting loosely within the barrel so that there is an air space between the outer surface of the chamber E and the inner surface of the fountain A. From the closed end of the chamber E a rod, e, passes through the 35 perforation d of the gland D, and is provided with a finger piece E' to which is connected an outer sleeve E'' which serves as a support against cross-strains when the rod e is extended outside the gland and also 40 provides a finish. The feed-bar B is provided with a central opening, b, coincident with the longitudinal axis of the fountain, and secured in line with this aperture and connecting therewith is a pipe F extending 45 axially of the fountain to and within the chamber E. The end of pipe F, within the chamber, is closed by a collar f, which serves not only to plug the end of the pipe F but also as a stop and below collar f, and aperture f' is formed in the side of pipe F connecting with the interior of the pipe. A 50 short distance below collar f and aperture f' a second stop f'' is positioned and mounted on pipe F between the two stops is a disk G fitting pipe F and frictionally engaging at 55 its outer edges or sides, the inner walls of

chamber E. It will be observed that, at the open end of the chamber E and extending upward, the wall of the chamber is slotted, as at e''' for a purpose hereinafter explained. 60

It will now be obvious that upon actuation of the chamber E in either direction, by means of the rod, e, the disk G by virtue of its frictional engagement with the inner side of the walls of chamber E will move 65 with the chamber within the limits of motion prescribed by the stops f, f'' upon the pipe F. When the chamber E moves up or rearwardly, its first movement carries the disk from its forward position abutting the 70 stop f'' to its rearward position, abutting stop f, in so moving covering aperture f' in pipe F. Continued rearward movement of chamber E will, as the chamber reaches the limit of its movement in this direction, 75 bring the upper or inner ends of slots e''' above the upper or inner surface of disk G opening communication between the inside of chamber E and the inside of fountain A. The movement of the chamber, as described, 80 has rarefied the air within the chamber and as soon as communication is opened, air enters from the fountain to fill the partial vacuum. Upon a reversal of movement, the initial movement of the chamber carries the 85 disk G with it and opens the aperture f'. The disk stopping against stop f' the chamber continues carrying the slots e''' below the upper or inner surface of disk G, closing communication between the inside of 90 the chamber and the inside of the fountain and trapping the air in the chamber, which is then by further movement of the chamber, forced through aperture f', pipe F, and aperture b in feed-bar B, out of the fountain 95 pen, the extruded air being replaced in the fountain by ink forced through the ink feed channel b' in the feed-bar, by atmospheric pressure, the lower or pen end of the fountain being submerged in an ink supply, as 100 will be understood.

It will be observed that in my improved fountain pen the chamber E is combined by means of an actuating rod e with a gland D closing the rear end of the fountain. This 105 is a practical feature of importance as by means of such a gland as I have shown, it is possible to close the rear end of the fountain fluid tight and to maintain this condition, which is an essential of successful operation 110 in order to obtain the desired filling action by means of an air pump of the cylinder and

22

piston type, completely enclosed within the fountain but distinct in all its parts from the fountain. Air from the fountain is drawn into the air pump and extruded from the pump and fountain through a suitable air duct connected to the air pump, ink simultaneously entering through the ink feed fissures to replace the extruded air. This is a feature of my improvement. As a practical matter the utilization of the fountain as the cylinder or chamber element of a piston pump is undesirable as it is difficult and expensive to form the inner walls of the fountain to a true contour or to give them a sufficiently smooth surface to prevent leakage and undue friction and wear of the piston element. The provision of an air pump entirely independent of the fountain and entirely enclosed therein is therefore of practical importance. A secondary feature of my invention is the fact that preferably the chamber E, constituting a part of the air pump, is not fitted to the interior of the fountain, but is loose therein, with air space at the sides thereof, the chamber being guided in its longitudinal movements by the disk G and pipe F. The chamber E it will be observed forms the cylinder element of an air pump, while the disk G and pipe F form the piston element of the air pump.

At the lower edge of the chamber E, I have shown an inwardly projecting element, h, which is in fact an annulus, screwed into place. The function of this annulus is that in the possible case of the disk G becoming fast to the pipe F, due to the drying of ink between the parts, the annulus, h, as the chamber E is drawn rearwardly or up, will contact with the disk G and forcibly disengage it, so that it may thereafter function as designed, by frictional actuation. At the upper end of the chamber E, within, a cavity, h', is formed to receive the collar f.

This cavity is slightly deeper than the thickness of the collar f, as that, in case the disk G is gummed and sticks at its upper or rearward position, the outer edge of the cavity h' will contact with the disk G on the down stroke and forcibly disengage it, so that it may thereafter function as designed by frictional actuation.

I claim:

1. In a fountain pen, a fountain, carrying a feed bar and pen at its front end; a gland, closing the rear end of the fountain; a movable cylinder, loosely fitting within the fountain and open at its front end; a rod, fast to the closed end of the cylinder and passing through the gland; a pipe, within the fountain and arranged longitudinally thereof, opening without the fountain at the front end and into the cylinder at the rear end; a disk, mounted upon the rear end of the pipe between a pair of stops and frictionally engaging the inner walls of the cylinder; a passage from the inside of the cylinder, above the disk, to the inside of the fountain, opened and closed by the reciprocation of the cylinder.

2. In a fountain pen, an air pump, made up of a movable cylinder, closed at its rear end and open at the other end and having an inward projection at its open end; a pipe within the fountain and arranged longitudinally thereof, opening without the fountain at its front end and into the cylinder at the rear end; a disk mounted upon the rear end of the pipe between a pair of stops and frictionally engaging the inner walls of the cylinder; the outer edge of the disk projecting into the path of the projection, substantially as and for the purpose described.

Signed at Boston, Massachusetts, this tenth day of January, 1922.

OLIVER MITCHELL.
